PORTABLE MICROPHONE AND AMPLIFIER

William A. Zarth, East Orange, N. J., assignor to
Dictograph Products Company, Inc., New
York, N. Y., a corporation of Delaware

Application February 11, 1941, Serial No. 378,328

2 Claims. (Cl. 179—107)

This invention relates to telephony and relates more particularly to combined microphones and amplifiers of a compact type which renders them suitable for use in hearing aid devices and other small portable telephone systems.

In accordance with the invention, I have provided a small self-contained microphone and amplifier system which may be readily carried about from place to place and, in conjunction with a suitable pocket size power supply and receivers is particularly useful in hearing aid systems.

Preferably, the microphone is of the crystal type and is combined with a vacuum-tube type of amplifier which includes tubes of such size that they may be disposed in the same casing with the microphone together with the necessary transformers, choke condenser and the like, to make a completely self-contained construction which may be readily carried in the pocket or suspended by a clip from, for example, the vest or coat of the individual using the same.

The device, in accordance with the invention, is substantially the same in size as the conventional microphone alone that is used with such hearing aid devices, and therefore, is no more conspicuous or unwieldy than such conventional microphones, and at the same time, has a gain which is far greater than that of the so-called mechanical amplifiers which are commonly used with portable hearing aid devices.

For a better understanding of the present invention, reference may be had to the accompanying drawings in which:

Fig. 1 is a view in front elevation of a typical form of the microphone amplifier embodying the invention;

Fig. 2 is a view in front elevation of the device in Fig. 1, shown with the front section of the casing thereof removed;

Fig. 3 is a view in section of the device taken on line 3—3 of Fig. 2; and

Figs. 4 and 5 are a diagrammatic showing of typical amplifier circuits used in the device.

As best shown in Fig. 1, the preferred form of the device is provided with a flat generally tear-drop shape of casing 10 which is provided with a grille opening 11 in front of the microphone diaphragm 12, best shown in Fig. 1. The casing 10 is preferably formed in two parts, the front section 13 of which is removable in order to expose the microphone and the various elements forming the amplifier for the device.

As shown in Fig. 2, the microphone diaphragm 12 which is of the conical type is mounted in the upper center of the casing and, as shown in Fig. 3,

has its edge supported by suitable brackets 14 on the back section of the casing 15.

The center of the diaphragm 12 is connected to one corner of the crystal 16 which is fixed to the back casing section 15, so that upon vibration of the diaphragm in response to voice waves, the crystal will be subjected to a twisting movement which causes the generation of a signal voltage.

10 The two tubes 17 and 18 of the amplifier which are of the new small "peanut" type, and in the preferred form of the invention may be the CK501 and CK503 pentode tubes, are also mounted in the casing section 15 and are disposed partially behind the edge of the microphone diaphragm 12 in order to conserve space. The tubes 17 and 18 are retained in the casing by means of small C-shaped clips 19 and 20 which may be secured to the section 15 in any desired way, such as, for example, by screws 21.

25 The screws 21 also support a combined switch and rheostat element 22 which consists essentially of a strip of insulating material 23 having a resistance coil 24 with which a slider 25 may be brought into engagement. The slider has two resilient fingers 27 and 28, the former engaging the coil 24 and the latter engaging a metallic strip 28 mounted behind the coil 24 to complete the circuit between the batteries, not shown, and the remainder of the circuit. The slider 25 is mounted on a metal bar 29 which is fixed in the upper end of the casing section 15 and is provided with a knob 30 by means of which it may be moved from "off" position out of engagement with the coil 24, across the coil 24 to vary the resistance in the circuit.

30 In the lower section of the casing 15 is a supporting plate or sub-panel 31 of insulating material on which are mounted a choke coil 32 and a transformer 33, these elements being connected by suitable wiring to the remainder of the elements, as will be presently described.

35 The supporting plate 31 is detachably connected to the casing section 15 to facilitate assembly and repair, if required. The section 15 is also provided with a plurality of jack sockets 34 which are suitably connected in the circuit so that the batteries and the receiver may be readily connected to and disconnected from the microphone and amplifier.

40 Any suitable type of amplifier circuit may be used in the device and I have found that the circuits disclosed in Figs. 4 and 5 are entirely satisfactory. The amplifier circuits may, as shown in Figs. 4 and 5, be of the impedance

coupled type in which the microphone crystal 16 is connected between the filament 35 and the grid 36 of the tube 17. The output from the plate 31 is fed to the choke or impedance 32 and through a blocking condenser 37 to the grid 38 of the tube 18. The plate 39 of the tube 18 is coupled through the transformer 33 to the receiver 40 which is shown diagrammatically.

The circuit disclosed in Fig. 5 differs from that disclosed in Fig. 4 in that it includes a condenser 41 which is connected in parallel with the choke 32 to permit tuning of the circuit and the elimination of unwanted frequencies.

The voltage output of the amplifiers is controlled by means of the combined switch and rheostat or voltage control 22 which by variation in the amount of the resistance interposed in the filament circuit of the tubes 17 and 18 varies the filament voltage supplied to the tubes 17 and 18.

The device preferably is provided with some means for attaching it to the vest or coat of the user, such as, for example, the spring urged clip element 42 which is fixed to the back of the casing section 15, thereby permitting it to be suspended, for example, from the vest pocket or outer coat pocket of the wearer.

From the foregoing description of a typical form of combined microphone and vacuum tube amplifier it will be apparent that I have provided an efficient yet extremely compact construction which eliminates the need of a separate amplifier system.

The device permits the frequency response of the microphone and the receiver to be varied to produce the most suitable frequencies to complement the defective hearing of the user and, because of the high gain of the device, permits the wearer who has defective hearing to hear much better than was possible with the low gain mechanical amplifiers of comparative size which were heretofore used.

While the invention has been described with reference to one particular type of device, it will be understood that the shape and appearance of the casing may be varied; different circuits than those described and different types of tubes may

be used in such circuits with equal facility, so long as the device is of a compact nature and is readily portable. Therefore, the form of the invention described above should be considered as illustrative and not as limiting the scope of the following claims.

I claim:

1. A portable microphone and amplifier for hearing aid devices comprising a casing having a grille adjacent one end thereof, means for suspending the casing from the clothing of the user, a crystal microphone secured to the back of said casing having a diaphragm disposed within said casing behind said grille, an impedance coupled amplifier including miniature vacuum tubes, a transformer and a choke within said casing, means for securing said tubes at least in part behind said diaphragm, a series of jacket sockets in another end of said casing, a sub-panel extending from adjacent to said jack sockets to adjacent the diaphragm, said sub-panel supporting said transformer and said choke, a combined switch and volume control in said one end of said casing and a circuit connecting said microphone, amplifier, jack sockets and switch and volume control, whereby said microphone and amplifier may be connected to an independently supported source of electrical energy and a receiver.

2. A portable microphone and amplifier unit for hearing aid devices comprising a casing of relatively flat form adapted to be worn by a user, said casing having a back with means thereon for attaching the casing to the user's clothing, a microphone located within the casing and including a conical diaphragm facing toward the front of the casing, vacuum tubes located in said casing and disposed adjacent the marginal portions of said diaphragm and between said portions and the back of the casing, a sub-panel located in said casing beside said diaphragm and parallel to the back thereof and supporting a choke coil and transformer and means on said casing for electrically connecting said sub-panel and the elements supported thereby to an independently supported source of energy and a receiver.

W. A. ZARTH.
